(57) **CLAIM**

The ornamental design for a smart thermostat device, as shown and described.

DESCRIPTION

FIG. 1 is a top plan view of a smart thermostat device, showing a new design;

FIG. 2 is a front plan view of a smart thermostat device in accordance with another embodiment, showing a new design;

FIG. 3 is a front plan view of a smart thermostat device in accordance with another embodiment, showing a new design;

FIG. 4 is a front plan view of a smart thermostat device in accordance with another embodiment, showing a new design;

FIG. 5 is a front plan view of a smart thermostat device in accordance with another embodiment, showing a new design;

FIG. 6 is a front plan view of a smart thermostat device in accordance with another embodiment, showing a new design;

FIG. 7 is a front plan view of a smart thermostat device in accordance with another embodiment, showing a new design;

FIG. 8 is a front plan view of a smart thermostat device in accordance with another embodiment, showing a new design;

FIG. 9 is a front plan view of a smart thermostat device in accordance with another embodiment, showing a new design;

FIG. 10 is a first side view of the design depicted in FIG. 1; FIG. 11 is a second side view of the design depicted in FIG. 1;

FIG. 12 is a top view of the design depicted in FIG. 1;

FIG. 13 is a bottom view of the design depicted in FIG. 1; FIG. 14 is a back plan view of the design depicted in FIG. 1;

The respective first side, second side, top, bottom and back plan views for the design depicted in FIG. 1 and illustrated in FIGS. 10-14, respectively, are identical to and representative of the first side, second side, top, bottom and back plan views for the designs depicted in FIGS. 2-9, respectively, and thus additional identical redundant Figures are not included herein at this time;

FIG. 15 is a top perspective view of the design depicted in FIG. 7;

FIG. 16 is a top perspective view of the design depicted in FIG. 8;

FIG. 17 is a top perspective view of the design depicted in FIG. 9;
